UNITED STATES PATENT OFFICE.

ABEL E. CHERNACK, OF PROVIDENCE, RHODE ISLAND.

LOOM.

1,117,791.

Specification of Letters Patent. Patented Nov. 17, 1914.

Application filed May 2, 1912. Serial No. 694,645.

To all whom it may concern:

Be it known that I, ABEL E. CHERNACK, a subject of the Czar of Russia, residing in the city of Providence, in the county of Providence and State of Rhode Island, have invented certain new and useful Improvements in Looms, of which the following is a specification.

The main object of my invention is to so construct a loom that a large shuttle containing a large bobbin of weft thread and therefore of considerable weight can be driven positively and at suitable speed through a shed of any desired width. In connection with my improvements in the shuttle mechanism, there are certain other features of improvement which are fully described hereinafter.

In the accompanying drawings Figure 1 is a sectional elevation showing the principal parts of a loom embodying my invention; Fig. 2 is a corresponding end elevation of the complete loom; Fig. 3 is a front elevation of the same with a part in section, and with parts broken away to get the view within the limits of the sheet; Fig. 4 is a diagrammatic plan view of the shuttle and its drivers; Fig. 5 is a vertical section of the reed frame and raceway, drawn to a larger scale; Fig. 6 is a plan view, partly in section, of the reed frame and raceway; Fig. 7 is a side elevation of the shuttle frame detached, with one of the bearings in section; Fig. 8 is an end elevation of the shuttle frame; Fig. 9 is a sectional view on the line 9—9, Fig. 2, drawn to a larger scale.

Although my invention may be applied to a loom with vertical heddles and horizontally arranged warps, I prefer to apply my improvements to a loom in which the heddles are horizontal and the warps travel vertically downward, and I have shown my invention embodied in a loom of this latter type in the accompanying drawings.

The frame F of the machine, which may be of any suitable construction, supports at its upper part a warp beam B, from which the warp threads pass under two rollers b, b, and over a roller b¹ and are thence led downwardly through the eyes of the heddles H, H¹. These heddles lie in horizontal planes and are reciprocated horizontally from right to left of Figs. 1 and 2 by suitable means. I will hereinafter describe one such means which may be employed. Suitable means, such as hereinafter described,

may be employed to intermittently raise and lower the roller b¹, to keep the warp threads under uniform tension during the closing and opening of the shed. From the heddles H, H¹ the warp threads pass through a set of horizontal reed bars R, R, (Figs. 1, 5 and 6), the ends of which are secured in bars F extending across from one side frame to the other of the machine. These bars are separated by spacing blocks 53, Figs. 5 and 6. As shown in Fig. 5, the undersides of the reed bars are cut out to provide dovetailed or undercut grooves, constituting a raceway R¹, (Fig. 5), in a horizontal plane for the shuttle, C. This shuttle is pendent from the raceway and comprises an open frame 40 with dovetailed or undercut edges 41 to run in the reed raceway R¹, end frames 42 and bottom cross bar 43, (Figs. 7 and 8). The end frames are provided with suitable bearings 44 for the journals of the bobbin A, which, because of my invention, can be of large size to carry a quantity of thread. The shuttle frame is provided with an extension piece 77, (Figs. 1 and 3), with a guide for the thread to be laid in the shed of the warps.

The described shuttle frame has bearings 45 for rollers E, whose axes carry at their upper ends pinions e, e. These pinions are adapted to mesh with fixed racks on the frame. For convenience the reed bars may be used to provide the racks, as shown in Figs. 5 and 6. By this means, as the shuttle is traversed backward and forward through the raceway, the rollers E are positively and correspondingly rotated, and the sizes of the pinions and rollers are such that the rollers have a surface speed equal to the lineal speed of the shuttle. I prefer to use four of these rollers, two on each side of the shuttle frame. I also prefer to use in coöperation with them shuttle drivers D, D, Fig. 4, arranged outside the warps, and one on each side of the shuttle. Each driver D comprises an upright frame 30 with a slide 31 mounted to travel back and forth in a guideway 32 in the cross bar F¹.

At each end of the frame 30 is a vertical bearing for a spindle 37, carrying at its lower end a pinion 38 to gear into a rack 35 formed on the inner face of the fixed plate 30. On the upper end of each spindle 37 is a roller G, lying in the same horizontal plane with the closely adjacent roller E on the shuttle frame. Thus as each driver D

is traversed back and forth in its guideway 32, the rollers G are positively rotated.

As shown in Fig. 4, the rollers G on the drivers D stand outside of, but overlapping the respective adjacent rollers E on the shuttle, so that when the drivers are traversed in either direction in their guideways, the rollers G bearing against the rollers E will carry the shuttle along.

10 The warps, as shown in Figs. 1 and 4, pass between the rollers G and E, but since both these rollers are positively rotated and with an equal speed of movement of the shuttle, there will be no rubbing action upon the warps to wear them out or break them. It is, 15 however, preferable to make these rollers or their surfaces of semi-hard material such as rawhide or rubber. In some cases, one shuttle driver D on one side of the shuttle will suffice.

20 I will describe a mechanism which may be used for imparting motion to the shuttle drivers. As illustrated in Figs. 2 and 3, each shuttle driver D has attached to its opposite ends a rope 55 passing over pulleys 56 on extensions 110 of the side frames of the machine. Thence these ropes 55 are coiled upon spirally grooved drums 57 and then pass under guide pulleys 58, Fig. 3, to the pulleys 56 at the other side of the machine. 25 These grooved rope drums 57 are keyed to a shaft 59 mounted in fixed bearings 60 and 61 on the side frame. The latter bearing is screw-threaded to receive the screw-threaded 30 end 62 of the shaft 59. The bearing 60 is smooth and such as to permit a slight end-wise motion of the shaft 59 therein, in order that as the shaft 59 is rotated the screw 62 in the threaded bearing 61 may give an end-wise motion to the shaft to aid the proper 35 winding and unwinding of the ropes 55 upon the drums 57. Necessary back-and-forth rotary motion is imparted to the shaft 59 by means of an upright rack 63 meshing with a 40 toothed portion 64 of the shaft 59, (Fig. 9), and guided in a guide piece 164 so mounted upon the shaft 59 as to be free to rock thereon to the necessary extent. The lower end of the rack 63, Figs. 2 and 3, has a crank pin 45 connection 65 to a gear wheel 66 secured to the shaft 67. This gear wheel meshes with a pinion 68 on the driving shaft 69, which is provided with a driving pulley and friction pulleys 70, 71. The friction pulley is 50 controlled from a hand wheel 72, whose spindle 73, Fig. 2, is screw-threaded into a knuckle 74 pivoted to a bent lever 75, which may swing upon a fixed center 76 so that the opposite end of this bent lever 75 may move 55 the friction pulley toward or from the driving pulley. As the gear wheel 66 revolves, the rack 63 will be traversed up and down in a swinging path and will impart rotary motion first in one direction and then in the 60 other to the shaft 59 carrying the rope

drums 57, which in turn will impart the necessary traversing motion to the shuttle drivers D, D and the shuttle.

I provide an oscillating beating-up comb 78, Figs. 1 and 2, mounted on an axis 79 in 70 bearings in the frame. This comb is oscillated on its pivot from the position shown in full lines to that shown by dotted lines in Fig. 1, to beat up the weft after the passage of the shuttle, and this may be done 75 through rod 80 and a lever 81 on a spindle 82 and having an arm 83 with an antifriction roller traveling in the groove of a cam 84 on the cam shaft 85, Fig. 1. To the same arm 81 is connected a rod 86 to impart motion to the roller 81. The cloth passes from the beating-up point downwardly and around rollers 87 and 88 to the take-up 80 drum 89.

90 The heddles H, H¹ may be actuated by any suitable means. In Fig. 1 I have shown indicated a mechanism which may be employed for the purpose. The heddles themselves are guided in guide pieces 90 on the top of the cross-frames F¹, F¹, and have 95 their opposite ends connected to straps passing over suitable idler and driving pulleys. Thus the heddle H is connected at the right-hand side in Fig. 1 to a strap 91 passing over an idler pulley 92 and thence wound upon and having its end attached to a pulley 93. To the same pulley there is fastened the end of a strap 94 but wound in the opposite direction and passing over the idler pulley 95 and connected to the 100 heddle H¹. At the left of Fig. 1, the heddle H is connected to a strap 96 passing over an idler pulley 97 and thence coiled upon a driving drum 98 and with its end fastened thereto. On the same driving 105 drum there is wound in the opposite direction a strap 99 passing over an idler pulley 100 and connected to the heddle H¹. Reciprocating motion may be imparted to the drum 98 by means of a quadrant 101 pivoted at 102 to the fixed part of the frame 110 meshing with a pinion 103 on the shaft 104 and the drum 98. To the quadrant 101 is pivotally connected a rod 105 connected to a rocking arm 106 pivoted to the shaft 82 and having its opposite end acted upon by a cam 107 (indicated by dotted lines) on the cam shaft 85. This cam shaft may receive its motion from the shaft 67, Figs. 2 115 and 3, through beveled gearing 108. 120

I claim as my invention:—

1. A loom having a shuttle and a race-way therefor, in combination with driving means for the shuttle, outside the warps, co-operating rollers on the driving means and the shuttle, and means whereby the rollers on both the driving means and shuttle are positively and correspondingly rotated as the shuttle is traversed to and fro. 125

2. A loom having a shuttle and a race- 130

way therefor, in combination with drivers on opposite sides of the shuttle, outside the warps, means for traversing said drivers, co-operating rollers on the drivers and shuttles and means whereby the rollers on the drivers and the shuttle are positively and correspondingly rotated as the shuttle is traversed.

3. A loom having heddles, a shuttle and a stationary raceway therefor, in combination with means for positively driving the shuttle to and fro in the raceway, said shuttle and driving means having coöperating rollers between which the warp threads pass, and gearing whereby the rollers on one of said parts are positively rotated as the shuttle is traversed to and fro.

4. A loom having heddles, a shuttle, a stationary raceway therefor, and means for positively driving the shuttle to and fro in the raceway, coöperating rollers on the driving means and the shuttle and means whereby the rollers on both the driving means and the shuttle are positively and correspondingly rotated as the shuttle is traversed to and fro.

5. A loom having horizontal heddles, reed bars under-cut to form a horizontal raceway, and a shuttle pendent in said raceway, in combination with drivers on opposite sides of the shuttle, outside the warps, and coöperating rollers on the drivers and the shuttle and means for traversing said drivers.

6. A loom having horizontal heddles, reed bars under-cut to form a horizontal raceway, and a shuttle pendent in the raceway, in combination with drivers on opposite sides of the shuttle, outside the warps, coöperating rollers on the drivers and the shuttle, means for traversing the drivers and means whereby the said rollers are posi-

tively and correspondingly rotated as the shuttle is traversed to and fro.

7. A loom having a shuttle and a stationary raceway therefor in combination with driving means outside the warps for traversing the shuttle to and fro, coöperating rollers on the driving means and on the shuttle, pinions carried by both said rollers, and stationary racks with which said pinions are geared, for the purpose set forth.

8. A loom having reed bars forming a raceway and a shuttle in the raceway, in combination with drivers on opposite sides of the shuttle, outside the warps, coöperating rollers on the drivers and shuttle, pinions carried by the rollers, racks to gear with the pinions of the driver rollers, racks furnished by the reed bars to gear with the pinions of the shuttle rollers and means for traversing the drivers.

9. A loom having a shuttle and reed bars forming a raceway for the shuttle in combination with means outside the shed for positively driving the shuttle, with coöperating rollers on the shuttle and driving means, the rollers on the shuttle having pinions gearing with the reed bars, which form racks for said pinions.

10. A loom having a shuttle and reed bars forming a raceway for the shuttle, in combination with means outside the shed for positively driving the shuttle, with coöperating rollers on the shuttle and driving means, both sets of rollers having pinions and stationary racks geared to said pinions.

In testimony whereof I have signed my name to this specification, in the presence of two subscribing witnesses.

ABEL E. CHERNACK.
